CLAIM

The ornamental design for a light fixture with light bars, as shown and described.

DESCRIPTION

FIG. 1 is an upper front perspective view depicting a first embodiment of a light fixture with light bars;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a lower rear perspective view thereof;

FIG. 9 is a front perspective view depicting a second embodiment of a light fixture with light bars;

FIG. 10 is a front elevation view thereof;

FIG. 11 is a rear elevation view thereof;

FIG. 12 is a right side elevation view thereof;

FIG. 13 is a left side elevation view thereof;

FIG. 14 is a top plan view thereof;

FIG. 15 is a bottom plan view thereof; and,

FIG. 16 is a lower rear perspective view thereof.

Any details shown in broken lines in the figures form no part of the claimed design of the light fixture with light bars. The figures include surface shading, which represents contour and not surface ornamentation.
